UNITED STATES PATENT OFFICE.

ALBERT A. SPERRY, OF MERIDEN, CONNECTICUT, ASSIGNOR TO C. ROGERS & BROS., OF SAME PLACE.

DESIGN FOR A SPOON OR FORK HANDLE.

SPECIFICATION forming part of Design No. 16,798, dated July 13, 1886.

Application filed May 17, 1886. Serial No. 202,471. Term of patent 14 years.

To all whom it may concern:

Be it known that I, ALBERT A. SPERRY, of Meriden, in the county of New Haven and State of Connecticut, have invented a new Design for Spoon and Fork Handles; and I do hereby declare the following, when taken in connection with accompanying drawings and the letters of reference marked thereon, to be a full, clear, and exact description of the same, and which said drawings constitute part of this specification, and represent, in—

Figure 1, a face view; Fig. 2, a transverse section through the shank.

This invention relates to a design for the handle of spoons and like articles of table service; and the design consists in the configuration of the handle, as shown in the accompanying illustration and hereinafter described. At the lower end of the handle is the usual tine portion or bowl, as indicated in broken lines. From the tine portion the shank extends upward of equal width to the point *a*, where the handle proper commences. From the tine or bowl portion the surface of the shank is plain for a short distance, and from the termination of the plain portion to the said point *a* the shape is in the form of a cluster of four longitudinal ribs or beads, one, *b*, on the face, a second rib, *d*, on the rear, a third rib, *e*, on the right, and the fourth rib, *f*, on the left. (See Fig. 2.) On the face of the han-

dle is the representation of a transverse band at the upper and lower ends of the beaded portions. The ribs on the face and back are rounded to represent longitudinal beads. The ribs *c f* are also of a rounded shape. At the termination of the rib portion at each end a transverse ornamentation is preferably made; but this ornamentation may be omitted. From the upper end of the rib portion the handle gradually expands. This upper or handle portion may be of any desirable shape, it only being essential to the design that it shall terminate in handle shape.

I claim—

The design for spoon or fork handle, consisting of a shank extending from the tine and terminating at the opposite end in handle shape, the shank portion of the handle of equal width, the surface of the shank plain from the tine portion upward for a short distance, and from the termination of the plain portion the shank represents a cluster of four longitudinal beads, with a transverse band at the upper and lower ends of the beaded portion, as shown in the accompanying illustration.

A. A. SPERRY.
